UNITED STATES PATENT OFFICE.

GEORGE B. MCLEOD, OF WINDSOR, ONTARIO, CANADA.

BOILER-SETTING.

964,931.

Specification of Letters Patent. Patented July 19, 1910.

Application filed September 19, 1908. Serial No. 453,811.

To all whom it may concern:

Be it known that I, GEORGE B. MCLEOD, a subject of the King of Great Britain, residing at Windsor, county of Essex, Province of Ontario, and Dominion of Canada, have invented a certain new and useful Improvement in Boiler-Settings, and declare the following to be a full, clear, and exact description of the same, such as will 5 enable others skilled in the art to which it pertains to make and use the same, reference being had to the accompanying drawings, which form a part of this specification.

This invention relates to boiler settings; 10 it has for its object an improved fire resisting facing and finishing for the arches in which the boilers are set.

The sides of the fire-box and the cover to the smoke box are especially exposed to 15 the destructive action of the fire, and in practice these parts are destroyed much more rapidly than the other parts of a setting in which the boiler is arranged, and the object of this invention is to provide a water 20 lined, or water containing, box, or tubes, which is used in place of brick at the sides of the fire box, and over the smoke box where the flame of the fire turns to pass 25 through the fire flues to the front of the 30 boiler.

The drawing shows the device in operation, parts of the wall and some parts of the 35 iron boxes or tubes, which are used in place of brick at the sides of the fire box, and over the smoke box where the flame of the fire turns to pass through the fire flues to the 40 front of the boiler.

The drawing shows the device in operation, parts of the wall and some parts of the 45 iron boxes or tubes are broken away.

1 indicates the brick-work in which the boiler is set. At the sides of the fire box, just above the grate (which is not shown in the present drawing) are placed iron 50 boxes or tubes 2 and 3, made from sheets of iron held together with stay bolts 4, to be sufficiently strong to withstand the pressure that may be produced in them by the generation of steam; at the rear of the boiler 55 over the smoke box, is a similar iron receptacle for water, made as a box or tube, and arranged to cover the opening which is ordinarily made at the rear of the boiler, where the flame and hot products of combustion 55 turn on their way from the fire-box to the

smoke stack 6. This box 5 is also made of flat plates of iron held together by stay-bolts and made strong and substantial. These iron boxes or tubes are preferably put into communication with the boiler, so 60 that the water travels from the boiler through them, and returns to the boiler at a lower level. Thus the pipe 7 leads from the boiler just above the high water line, into the box 5, and the pipe 8 leads from 65 the box 5 into the box 3. The boxes 2 and 3 are connected by a connecting pipe 9, and one or both of them is connected into the under part of the boiler by a pipe 10. Thus connected up, there is no necessity for an 70 independent water connection to the boxes, although this invention is not confined to a system of protective boxes, in which there is an intermediate connection between the interior of the boxes and the interior of the 75 boiler, and the principal object of the invention is to protect the brick-work, and a secondary object is to utilize the heat imparted to these protected boxes or tubes, to heat the water which is converted into 80 steam for the purposes for which steam is 85 used.

What I claim is:—

In a boiler furnace having a fire box, a boiler having fire flues, side and end walls surrounding the boiler, vertically disposed 85 protection chambers adapted to contain water fitting against said side walls at a point adjacent the fire box and extending substantially from top to bottom thereof, a horizontally disposed protection chamber 90 adapted to contain water, said chamber resting upon the top of the furnace walls at a point to the rear of the boiler above the fire flues and constituting a cover, a steam conduit leading from the steam space of the 95 boiler into the horizontally disposed chamber, water conduits leading from the vertically disposed chambers to the water space of the boiler, and communicating pipes between the horizontally disposed protecting 100 cover and the vertically disposed protecting chambers.

In testimony whereof, I sign this specification in the presence of two witnesses.

GEORGE B. MCLEOD.
